UNITED STATES PATENT OFFICE.

ASHBERT CUOGHI, OF BROOKLYN, NEW YORK.

VALVE-GRINDER.

1,315,909.

Specification of Letters Patent. Patented Sept. 9, 1919.

Application filed June 22, 1918. Serial No. 241,396.

To all whom it may concern:

Be it known that I, ASHBERT CUOGHI, a citizen of the United States, residing at Brooklyn, in the county of Kings and State 5 of New York, have invented new and useful Improvements in Valve-Grinders, of which the following is a specification.

This invention relates to valve grinders, the object in view being to provide an accurate and reliable device for grinding the valves of engines and particularly the valves 10 of internal combustion engines, the improved valve grinder embodying a light portable electric motor supported by the frame of the device and serving to impart oscillatory motion to a valve oscillating head which is journaled in the frame of the device, the whole having combined therewith a novel arrangement of controlling 15 handles by means of which the device may be accurately and conveniently held in proper relation to the valve being ground and more or less pressure applied to the 20 valve manually during the grinding operation.

With the above and other objects in view, the invention consists in the construction, combination and arrangement of parts, as herein described, illustrated and claimed.

30 In the accompanying drawings:

Figure 1 is a top plan view of the valve grinder.

Fig. 2 is a bottom plan view of the same.

Fig. 3 is a side elevation of the valve 35 grinder.

Fig. 4 is a side elevation looking toward the opposite side.

Fig. 5 is an end view of the device looking toward the valve oscillating head.

40 Fig. 6 is an elevation looking toward the opposite end of the valve.

The valve grinder, contemplated in this invention comprises a frame designated generally at A, said frame having a bottom 45 wall 1 and upstanding walls 2 arranged in spaced parallel relation to each other. The frame also comprises a transversely extending top bearing plate 3 and extending upwardly from the latter is a tubular handle 4 socket 4, in which a suitable handle 5 is 50 detachably fitted.

Below the top bearing plate 3 there is mounted a normally vertical oscillatory valve turning head 6 which is mounted in a bearing 7 in the top plate 3 and which also 55 extends through a bearing 8 in the bottom of the frame beneath which, said oscillatory head is provided with a bit receiving chuck 9 having a tool holding set screw 10 enabling different tools to be used in conjunction with 60 the valve grinding device, said tools being shaped to engage valve heads of different types and designs in order to impart oscillatory movements to the valve to effect a grinding of the valves and valve seats. 65

Extending off from one side of the head 6 is an operating arm 11 to which is connected by a universal joint 12, a rod or pitman 13 which is connected to a wrist pin or crank arm 14 extending from one side of a gear 15 70 mounted upon a rotary shaft 16 journaled in the upright portions 2 of the frame. The gear 15 meshes with a pinion 17 on a countershaft 18 having also fast thereon a gear 19 which meshes with a pinion 20 on the 75 armature shaft 21 of a small electric motor 22 which is supported between the side members 2 of the frame and supported in relation thereto by cross members or pins 23.

Secured fixedly to the bottom 1 of the 80 frame is a longitudinally extending tubular handle socket 24 in which a removable handle 25 is fitted. The device is thus provided with two handles, one of which stands in a normal vertical position and the other 85 of which stands in a normal horizontal position. This arrangement of handles enables the device to be accurately manipulated and held during the valve grinding operation and it also enables any desired 90 pressure to be brought to bear on the valve during the grinding operation as said vertical handle is positioned directly above and in line with the valve turning tool. By means of the horizontally extending handle, 95 the device, as a whole, may be bodily turned, during the grinding operation so that the valve and valve seat may be ground uniformly and accurately.

I claim:

A portable hand implement for grinding valves, comprising a frame, an oscillatory

valve turning head journaled in said frame, an electric motor mounted in said frame, connecting means between said motor and said oscillatory heads, for actuating the latter, a pressure regulating handle extending upwardly from said frame, and a second

handle extending from said frame substantially at a right angle to the first named handle, for turning the frame and varying the limits of oscillation of the valve.

10

In testimony whereof I affix my signature.

ASHBERT CUOGHI.
